UNITED STATES PATENT OFFICE.

ALBERT B. DEEM, OF INDIANAPOLIS, INDIANA.

AUTOMATIC OIL-BURNER.

1,253,794.

Specification of Letters Patent. Patented Jan. 15, 1918.

Application filed December 26, 1916. Serial No. 138,970.

To all whom it may concern:

Be it known that I, ALBERT B. DEEM, a citizen of the United States, and a resident of Indianapolis, county of Marion, and State of Indiana, have invented a certain new and useful Automatic Oil-Burner; and I do hereby declare that the following is a full, clear, and exact description thereof, reference being had to the accompanying drawings, in which like letters refer to like parts.

This invention relates to an oil burner for furnaces or boilers used in locomotives, steam ships, forging plants, glass factories and the like, which is adapted to take the place of the ordinary type of oil burner, reference being had to my prior application Serial No. 101,842, filed June 5, 1916. This burner is especially constructed so that carbon will not be formed from the burnt oil on the walls of the furnace, and while it burns at an even and steady heat, it uses only one-half of the oil that the ordinary burner uses.

One of the features of the invention is the needle valve which is pneumatically operable for cleaning out the oil outlet when it becomes clogged, so that by the operation of a valve in an air line, the clogging material may be removable from the outlet without taking the burner off, and at the same time the sediment or dirt may be blown out of the burner by compressed air so that it will be quickly and thoroughly cleaned. The construction of my burner makes this operation so simple that it may be cleaned out at short intervals without losing any appreciable time, whereby the burner will be kept in better condition, thereby being more efficient and giving better service. The cleaning needle is incased so as to be protected from outside injuries and is also provided with a guide so that the operator cannot break or bend it, as was often the case in the old construction.

Another feature of the invention is the means for further breaking up the oil spray which consists of a set of cross wires secured directly in the path of the oil stream or spray at the mouth of the burner.

The full nature of the invention will be understood from the accompanying drawings and the following description and claims:

In the drawings, Figure 1 is a plan view

looking down on the burner. Fig. 2 is a side elevation. Fig. 3 is a central longitudinal cross section showing the device in operative position. Fig. 4 is the same as Fig. 3, showing the device in cleaning position.

In the drawings there is shown a burner having a casing 10 with a nozzle casing 11 adapted to be tightly screwed on the end thereof. In said casing there is an oil inlet chamber 12 to which there is connected an oil line 13. Separated from said oil chamber by an upwardly extending partition 14, there is a reservoir 15 which is adapted to catch any foreign substance or matter which may be deposited by the oil passing over it. Said reservoir has a removable valve outlet or pet cock 16 which may be utilized in draining and cleansing the burner.

Extending longitudinally of the casing 10 there is an inclosed passageway 17 having an end cap 18 secured to the end thereof. Through the center of said end cap there is a small passage or opening 19 which serves as an oil outlet, through which the oil is forced under pressure. Extending longitudinally through said passageway there is a valve rod 20 having a piston 21 secured at one end thereof and a needle point 22 on its other end which has a beveled portion 23 adapted to seat in the opening of the valve 19 with a projection adapted to extend through said opening of the valve. The piston 21 is adapted to reciprocate in a cylinder 24 which is closed at one end by a cap 25 which is provided with an inwardly projecting lug 26 against which said piston is adapted to be forced by a coiled spring 27. Said spring surrounds the rod 20 and rests between the piston and inner end wall of the cylinder so as to return the piston and rod to the position shown in Fig. 3 after the operation thereof. The inner end wall of the cylinder is provided with ports 28 to permit the escape of air from the cylinder 24 when the piston is operated. There is also a port 29 forming a passageway between the cylinder 24 and the chamber 12.

There is an air chamber 30 which surrounds the oil passageway 17 and the cap 18 and has an inlet 31 suitably connected to a pressure pump or compressed air chamber, not shown herein. Said inlet is regulated by a butterfly valve or damper 32 pivoted therein and secured on a shaft 33 on which

there is a thumb piece 34 for operating said butterfly valve to shut off or regulate the air supply. In the end of the cap 11 there is an opening 35 through which the mixture passes into the furnace. The air chamber 30 is cut off from the oil chamber 12 by a wall 36 so that there will be no mixture of air or oil until after the oil has been forced into a spray.

10 Communicating with the cylinder 23 there is a compressed air inlet 37 provided with a shut-off valve 38. Connecting said air inlet with the air inlet 31 there is a pipe line 39 which may be formed of flexible steel 15 tubing.

On the cap 18 there is an inwardly extending guide 40 which engages the rod 20 so as to hold it in position at all times and guide it into the opening 19. On the other 20 end of said cap there are outwardly extending lugs 41 provided with cross wires 42 which cross each other directly in front of the opening 19 and further act to break up the oil spray.

25 When the burner is in the position shown in Fig. 3, the compressed air enters the chamber 30 surrounding the oil passage 17 and passes on through the outlet 35. The oil enters through the line 13 under pressure, the oil chamber and through the opening 19 where it engages the compressed air to form an oil spray or vapor. The dirt and sediment will be blown out of the chamber 12 into the reservoir 15 where it will 30 settle at the bottom or will be forced into the opening 19 which occurs in burners of the ordinary type, thereby clogging up the nozzle and preventing the operation of the burner. When this occurs, the butter-fly 35 valve is closed, as in Fig. 4, and the valve 40 38 opened so that the compressed air is forced into the cylinder 23 and acts against the piston 21 to force the point 22 through the opening 19 for clearing it of any matter 45 that may be clogging it. The air then escapes through the passage 28 and being shut off from the air chamber 30, has its only escape through the outlet 16 blowing the sediment and dirt out with it.

50 It may be, therefore, readily seen that the burner will be thoroughly cleaned by closing the butter-fly valve 32 and opening the valve 38 without danger of breaking the needle point 22 or bending the rod 20, as has here- 55 tofore been found to be the case.

The invention claimed is:

1. An oil burner having a housing, an air chamber in said housing, an oil chamber having a valve opening communicating with 60 said air chamber through which the oil is forced under pressure, a rod adapted to extend into said opening, a piston secured to one end of said rod, means for conveying air to the rear of said piston and actuate the 65 same whereby said rod will close said valve

and force any foreign matter therefrom and means for conveying said air from the rear of said piston into said oil chamber for cleaning said oil chamber of foreign particles.

2. An oil burner having a housing, an air chamber therein, an oil chamber having a valve opening communicating with said air chamber, a rod having one end adapted to seat in said valve opening and extend 70 through said opening, a piston on the other end of said rod, a cylinder in which said piston is adapted to reciprocate, a compressed air passage communicating with said air chamber, an air line communicating with 75 said passage and cylinder, a spring for returning said piston to its normal position after having been operated by the air forced into said cylinder and a by-pass for conveying the air from the rear of said piston into 80 said oil chamber when the piston is moved forward, whereby sediment or the like will be blown from the oil chamber.

3. An oil burner having a housing, an air chamber therein, an oil chamber having a 90 valve opening communicating with said air chamber, a rod having one end adapted to seat in said valve opening and extend through said opening, a piston on the other end of said rod, a cylinder in which said 95 piston is adapted to reciprocate, a compressed air passage communicating with said air chamber, an air line communicating with said passage and cylinder, a spring for returning said piston to its normal position 100 after having been operated by the air forced into said cylinder, a valve in said air line and means for operating said valve whereby the air will be excluded from said air chamber and caused to enter said cylinder through 105 said air line.

4. An oil burner having a housing, an air chamber, an oil chamber having a valve opening communicating with said air chamber, an air inlet having a damper therein, 110 a reservoir through which oil must pass to said oil chamber, means connected with said reservoir for draining it, a rod having one end adapted to seat in said valve opening and extending through said opening, a piston secured to the other end of said rod, and means for introducing compressed air into 115 said housing when said damper is moved to closed position for operating said piston whereby said valve opening will be closed 120 and sediment removed therefrom.

5. An oil burner having a housing, an air chamber in said housing, an air inlet having a valve therein, an oil chamber having a valve opening communicating with said air chamber, 125 a rod extending through said oil chamber having one end adapted to seat in said valve opening and extend through said opening, a piston on one end of said rod, a cylinder in which said piston is adapted to re- 130

ciprocate, an air line communicating said air inlet with said cylinder so that said piston will be operated thereby when said air inlet valve is closed, and a spring in said cylinder 5 for returning said piston to its normal position.

6. An oil burner having a housing, an air chamber in said housing, an air inlet having a valve therein, an oil chamber having a 10 valve opening communicating with said air chamber, a rod extending through said oil chamber having one end adapted to seat in said valve opening and extend through said opening, a piston on one end of said rod, a 15 cylinder in which said piston is adapted to reciprocate, an air line communicating said air inlet with said cylinder, so that said piston will be operated thereby, and a spring in said cylinder for returning said piston to

its normal position, said cylinder having an 20 opening whereby the compressed air may be forced through said housing for cleaning the sediment therefrom.

7. An oil burner having a housing, an air chamber therein, an oil chamber, a cap over 25 one end of said oil chamber having a valve opening communicating with said air chamber, means for introducing oil and air into their respective chambers under pressure, a plurality of lugs extending forwardly from 30 said cap, and crossed wires carried by said lugs and extending in front of said valve opening for breaking the oil stream and spray.

In witness whereof, I have hereunto affixed my signature.

ALBERT B. DEEM.
